US00D904151S

(12) **United States Design Patent** (10) **Patent No.:** **US D904,151 S**
(45) **Date of Patent:** **** Dec. 8, 2020**

(54) **STRAPPING DEVICE**

- (71) Applicant: **Signode Industrial Group LLC**,
Glenview, IL (US)
- (72) Inventor: **Samuel Hochstrasser**, Fällanden (CH)
- (73) Assignee: **Signode Industrial Group LLC**,
Glenview, IL (US)
- (**) Term: **15 Years**
- (21) Appl. No.: **29/739,016**
- (22) Filed: **Jun. 22, 2020**

Related U.S. Application Data

- (63) Continuation of application No. 29/722,914, filed on
Feb. 3, 2020, now Pat. No. Des. 889,229, which is a
continuation of application No. 29/705,106, filed on
Sep. 10, 2019, now Pat. No. Des. 874,897, which is

(57) **CLAIM**

The ornamental design for a strapping device, as shown and
described.

DESCRIPTION

FIG. 1 is a front top right-side perspective view of a
strapping device of one embodiment of my new design.

FIG. 2 is a front elevational view of the strapping device of
FIG. 1.

FIG. 3 is a rear elevational view of the strapping device of
FIG. 1.

FIG. 4 is a right-side elevational view of the strapping
device of FIG. 1.

FIG. 5 is a left-side elevational view of the strapping device
of FIG. 1.

FIG. 6 is a top plan view of the strapping device of FIG. 1.

FIG. 7 is a bottom plan view of the strapping device of FIG.
1; and,

FIG. 8 is a rear bottom left-side perspective view of the
strapping device of FIG. 1.

The broken lines in the drawings depict portions of the
strapping device which form no part of the claimed design.

1 Claim, 8 Drawing Sheets

Related U.S. Application Data

a continuation of application No. 29/598,733, filed on Mar. 28, 2017, now Pat. No. Des. 864,688.
